(57) **CLAIM**

The ornamental design for an electric scooter frame, as shown and described.

DESCRIPTION

FIG. 1 is a top elevation view of an electric scooter frame. FIG. 2 is a bottom elevation view of the electric scooter frame.

FIG. 3 is a front elevation view of the electric scooter frame.

FIG. 4 is a back elevation view of the electric scooter frame.

FIG. 5 is a left elevation view of the electric scooter frame.

FIG. 6 is a right elevation view of the electric scooter frame.

FIG. 7 is a front-left perspective view of the electric scooter frame.

FIG. 8 is a back-right perspective view of the electric scooter frame.

FIG. 9 is a back-left perspective view of the electric scooter frame; and,

FIG. 10 is a front-left perspective view of the electric scooter frame, shown in use.

The broken lines shown in the drawing are for the purpose of illustrating environmental structure and form no part of the claimed design.
